UNITED STATES PATENT OFFICE.

ROBERT P. WINSOR, OF AUBURN, RHODE ISLAND, ASSIGNOR TO WINSOR & JERAULD MANUFACTURING CO., OF PROVIDENCE, RHODE ISLAND, A CORPORATION OF MAINE.

TENTER CLIP.

Application filed May 16, 1923. Serial No. 639,325.

To all whom it may concern:

Be it known that I, ROBERT P. WINSOR, a citizen of the United States, residing at Auburn, in the county of Providence and 5 State of Rhode Island, have invented certain new and useful Improvements in Tenter Clips, of which the following is a specification.

This invention relates to an improved 10 construction of cloth clamp or tentering clip, and has for its object to provide a specially-constructed controller member for the swinging jaw of the clip, the same having an elongated, narrow downwardly-extending 15 arm or finger with a relatively thin feeling edge for engaging the fabric, whereby this controller is adapted to drop immediately upon reaching the edge of the fabric, between the edge and the loose threads 20 which may be looped along its edge as is the case in the tentering of ginghams and like fabrics.

With these and other objects in view, the invention consists of certain novel features 25 of construction, as will be more fully described, and particularly pointed out in the appended claims.

In the accompanying drawings:

Figure 1 is a sectional side elevation of a 30 tentering clip showing my improved controller member mounted therein with its feeling edge engaging the surface of the fabric to be engaged.

Figure 2 is the same as Figure 1 but showing the downwardly-extending arm of the controller as having dropped at the edge of the fabric between the fabric and the thread loop along its edge.

Figure 3 is a perspective view of my improved controller member.

Figure 4 is a view illustrating a fragmental portion of gingham fabric showing the loose thread as extending along the edge thereof.

In the weaving of such fabrics as ginghams where stripes of different colors are woven into the goods by different colored threads, when each shuttle carrying its thread of different color is called out of 45 action its thread is led loosely along the selvage of the fabric until this shuttle is again called into action to lay the threads in the next stripe of the same color.

When this fabric with its loose edge 50 threads is being passed through a tentering

machine these loose threads are found to interfere with the normal action of a tentering clip which has a controller with the usual broad feeling surface, as such a controller usually catches on one of these 60 threads and prevents the gripping jaw from engaging the selvage at the desired depth, that is, in some cases the clip may be permitted to engage the fabric as the proper 65 depth, while in other cases the fabric is gripped too closely to the edge, thus causing ununiformity in the depth of grip; and in still other instances the jaw may be held open so long by these loose threads that the 70 fabric will be entirely pulled away from the jaw before it is permitted to close causing what is known as "misclips" which effect is quite undesirable as the goods are thus damaged.

By the use of my improved construction 75 of clip these loose threads on the edge of the fabric will not interfere with the proper closing of the swinging jaw permitting the different clips to grip the fabric uniformly:—

With reference to the drawings, 10 designates the body of a clip having a fixed jaw 11 and a swinging jaw 12 pivotally mounted at 13 in the supporting arms 14 only one of which is shown.

In this clip member, I have mounted a controller member 15 which is pivoted at 16 and slotted at 17 to receive a roller 18 in the arm 19 of the swinging jaw, and this controller is provided with an elongated, 90 narrow, downwardly-extending arm or finger 20 which is provided with a relatively thin or pointed feeling end 21 which rides along the surface of the cloth 23, whereby as the cloth is drawn outwardly as it enters 95 the tentering machine this feeling end 21 of the arm 20 upon coming to the selvage edge 22 of the fabric will immediately drop between this edge and the loose threads 24 extending along the edge of the fabric thereby permitting the pivot arm 12 to swing into 100 position to engage the cloth exactly at the proper distance from its edge and so effectively prevent "mis-clips" and damage to the goods.

The controller arm 20 may be formed in hook-shape or in any other desired shape, the same being pointed or reduced and provided with a thin or narrow engaging or feeling end which is adapted to 110

work its way down between the loose edge threads and the edge of the fabric, said arm being of a length to extend down between the loose threads and the fabric edge, a distance sufficient to permit the engaging jaw 12 it controls, to drop and bite the fabric.

My improved construction of controller member is extremely simple and practical and is effective in its operation inasmuch as 10 by its use the swinging jaws of all of the clips of a tentering machine are caused to grip the fabric at a uniform distance from its edge and are not affected by the loose threads which are formed along the edge 15 of such fabrics as ginghams and the like.

The foregoing description is directed solely towards the construction illustrated, but I desire it to be understood that I reserve the privilege of resorting to all the mechanical changes to which the device is susceptible, the invention being defined and limited only by the terms of the appended 20 claims.

I claim:

25 1. A tenter clip having a fixed jaw, a swinging jaw, and a controller for said

swinging jaw having a feeler finger with a feeling end relatively narrow in a plane transverse to the edge of the fabric, whereby said end is adapted to drop between the 30 fabric and a loose thread looped along its edge.

2 A tenter clip having a fixed jaw, a swinging jaw, and a controller carried by said swinging jaw, the feeling portion of 35 said controller being in hook shape and having a work-engaging end thin in its dimension at right angles to the edge of the work whereby it is adapted to drop between the work and a loose thread looped along its 40 edge.

3. A tenter clip having a fixed jaw, a swinging jaw, and a controller for said swinging jaw having an elongated narrow downwardly-extending finger with a feeling 45 end, relatively thin in a plane transverse to the edge of the fabric whereby this end is adapted to drop between the edge of the fabric and a thread loosely looped along the edge thereof.

In testimony whereof I affix my signature.
ROBERT P. WINSOR.
